UNITED STATES PATENT OFFICE

ROGER BARTON, OF CHICAGO, ILLINOIS

RADIANT HEAT APPARATUS

Application filed December 2, 1929. Serial No. 411,194.

The principal object of this invention is to provide a simple instrument for use in studying radiant energy in the visible and infrared spectra, and, in general, of heat radiation, which object is admirably accomplished by the combination of a thermopile including a plurality of couples and a reflector which collects and concentrates heat on the "hot" junctions of the thermopile.

10 Further objects and advantages of the invention will be revealed as the description is read in connection with the accompanying drawing illustrating the preferred embodiment of the invention, and in which

15 Fig. 1 is a plan view, with the upper half of the collector and casing removed; Fig. 2 is a longitudinal vertical section; Fig. 3 is a front elevation; and Fig. 4 is a fragmentary plan view illustrating the construction of the thermopile couples.

20 But neither this specific illustration, nor the correspondingly specific description, is to be taken in a limiting sense, for they are used for the purpose of disclosure only, and it is intended that the substance of the invention shall be covered by the appended claims irrespective of the particular disclosure.

The apparatus illustrated in Fig. 1 includes a thermopile, generally indicated by A, a collecting reflector and casing, generally indicated by B, and a galvanometer, generally indicated by G.

25 The thermopile may, of course, be made of a variety of metals selected from the thermoelectric series, and also alloys of metals in that series, and some of the metallic sulfides, such as galena. From this list it will be sufficient to mention iron, constantan, bismuth, nickel, German silver, lead, platinum, copper, zinc, antimony, tellurium and selenium. The relative merits of these various substances are well known, and the selection of any two will be based upon the particular 30 object that may be attained by the peculiarities of a couple made of them. Generally speaking, No. 40 wire, or the equivalent in strips, will be found satisfactory in an estimate of the general nature illustrated in the drawing.

35 Preferably, and as illustrated, the thermopile is composed of a plurality of strips 10 and 11, of iron and constantan, respectively, having the ends overlapping and spot welded at 12 in numbers sufficient to form approximately 38 "hot" and "cold" junctions. Such a thermopile will develop about 50 microvolts per degree of temperature difference for each couple; thus the total E. M. F. developed per degree is of the order of 2 millivolts. On the 40 assumption that the resistance is of the order of 30 ohms, and that the galvanometer has approximately the same resistance, the current per degree elevation of temperature of the "hot" junctions is in the neighborhood of 45 32 microamperes. The galvanometer mentioned is sensitive enough to indicate .0004 of this current, hence a temperature elevation of the "hot" junctions of around .0004 degrees centigrade will be discernible.

50 The end strips of the thermopile are equipped with lead wires 13, for connection with binding posts 14.

55 The reflector and casing is composed of two similar aluminium die castings 15 and 16, secured together by bolts 17 passing through flanges 18.

60 The reflecting surface 19 is, for the want of a better term, called cylindro-parabolic, because in this preferred form it is conceived 65 as a surface generated by a right line moving parallel to itself along a parabolic path, whereby the foci of the reflecting surface are in a right line 20, in which the "hot" junctions 70 of the thermopile A may be located.

65 Another way of viewing the reflecting surface is such that all sections parallel to that shown in Fig. 2 are parabolas with foci in a line normal to the plane in which the section 75 is taken.

70 However, this cylindro-parabolic form is not indispensable, for theoretically, at least, a surface in which a transverse section would be curved, or in which the focal points would be on a curve, would also be suitable.

75 Adjacent to the right end and externally of the reflecting surface 19, as shown in Figs. 1 and 2, the castings 15 and 16 are cored out to form a cavity 21, which communicates 80 with the horn-like aperture bounded by the 85

reflecting surface and side walls through a narrow slot 22 in which the thermopile is clamped.

The strips 10 and 11 forming the thermopile are held in a frame made of two celluloid strips 23, corresponding surfaces of which have been softened by treating them with a solvent such as acetone or ether, and then pressed together against opposite sides 10 of the thermopile. This gives the thermopile a stability not inherent in the fine strips, and provides a convenient surface for clamping between the separate castings to hold the "hot" junctions in proper relation to the focal 15 line.

The cavity 21, when the reflector is made of aluminum or lined with aluminum, or some metal having a like high degree of conductivity, serves the important function of 20 protecting the "cold" junctions from undesired thermal influences. But though the dead air space within the cavity introduces a thermal lag before temperature changes in the reflector can affect the "cold" junctions, 25 and is a convenience in making electrical connections to the thermopile, it follows that the cavity may be omitted and the entire thermopile with the exception of the exposed "hot" junctions may be rigidly 30 clamped between the two halves of the reflector.

The lower casting 16 is equipped with a handle 24, by which the instrument may be handled or clamped to a suitably fixed support in the laboratory.

The construction of the thermopile and its mounting arrangements follow sound physical principles of design. The thermopile itself has small thermal capacity and small 40 heat conductivity away from the junctions. The "hot" junctions are desirably blackened to absorb the heat readily. The mass of metal pressed against the thermopile is so great, and the transfer of heat thereto so effective that there is no possibility of the 45 hot and cold junctions reaching temperature equilibrium. No further cooling means are necessary. The collecting aperture of the horn, in this preferred commercial form, is 50 seven and one-half centimeters square, and heat rays entering the collector over this entire area are so concentrated that the net intensification, with losses for absorption deducted, is about twenty times. The actual 55 temperature of the cold junctions can if necessary be determined, but in ordinary use they are assumed to be at room temperature. The thermal capacity of the reflector is so great that no significant change in temperature 60 will take place while any ordinary observation is being made.

Aluminum alloys in common use are especially suited for use in the casing because they lend themselves to die casting, present 65 an efficient reflecting surface and have ap-

propriate conductivity; but a variety of other materials, including copper, cuprous alloys, and the non-corrosive ferrous alloys, are obvious substitutes.

I claim as my invention—

1. In a device of the class described, a reflector in which parallel sections are parabolas having foci in line, said reflector having a narrow slot adjacent to the foci, and a thermopile including a plurality of "hot" 75 points mounted in said slot.

2. In a device of the class described, a casing including a reflector composed of many like conic sections with their foci in line, a cavity spaced from the reflector and connected with it by a narrow slot, and a thermopile composed of a plurality of couples mounted in the slot with their "hot" junctions in line with the foci and their "cold" junctions in 80 the cavity.

3. A device sensitive to radiant heat comprising a reflector having a multiplicity of foci arranged in a line, a thermopile having its hot junctions arranged to occupy the line of the foci and having its cold junctions located behind the reflecting surface and in thermal relation to the body of the reflector.

4. A device sensitive to radiant energy comprising a split cylindro-parabolic reflector having clamping faces located at the vertices of the parabolas, a thermopile having its hot junctions occupying the line of the foci at the parabolas clamped between the two parts of the reflector and having its cold junctions in thermal relation to the clamping faces.

5. A heat concentrating casing for radiant heat apparatus having a cavity in which the opposed walls are substantially straight in transverse section and parabolic in longitudinal section with the foci of the longitudinal sections lying in substantially a straight line normal to the planes of said longitudinal sections, and means associated with the casing adapted to support a thermopile with its hot junctions coincident with the line focus of the parabolic sections, and an extension in the rear part of the casing having a separate cavity adapted to house the "cold" junctions of the thermopile.

6. In a device of the class described, a reflector having a reflecting surface in which parallel sections are parabolas having foci in a line and a thermo-couple, the "hot" junctions of which are coincident with said line and the "cold" junctions of which are located externally of said reflecting surface in thermal relation to the body of the reflector and out of line of the heat rays falling on said reflecting surface.

7. In a device of the class described, a casing including a reflector having a reflecting surface composed of many like conic sections with their foci in a line and a thermocouple composed of a plurality of couples having

their "hot" junctions coincident with said line and their "cold" junctions located exteriorly of said reflecting surface in thermal relation to the body of the reflector and out of line 5 of the heat rays falling on said reflecting surface.

In testimony whereof I affix my signature.
ROGER BARTON.
